UNITED STATES PATENT OFFICE.

WALTER THOMAS CROSSE, OF COUNTY OF MIDDLESEX, ENGLAND.

WOODEN PANEL, LINING, CEILING, AND FLOOR FOR BUILDINGS, &c., AND PAVING FOR STREETS.

SPECIFICATION forming part of Letters Patent No. 705,737, dated July 29, 1902.

Application filed August 3, 1901. Serial No. 70,709. (No model.)

To all whom it may concern:

Be it known that I, WALTER THOMAS CROSSE, engineer, a subject of the King of Great Britain, residing at 13 Regent street, 5 in the county of Middlesex, England, have invented certain new and useful Improvements in Wooden Panels, Linings, Ceilings, and Floors for Buildings and other Structures and Paving for Streets, of which the following is 10 a specification.

This invention relates to improvements in wooden panels, linings, ceilings, and floors for buildings and other structures and paving for streets.

15 According to this invention one or more dovetail grooves are made in the back of a board, block, or lath. The sides of the boards, blocks, or laths may be square or may be made with ribs and grooves to fit one into the other. 20 The laths are fitted together back to back either with the dovetail grooves in the same direction or with the dovetail grooves at right angles to each other, and they may also be glued or cemented together or nailed or riveted. 25

The drawings illustrate constructions made in accordance with this invention.

Figure 1 shows a plan, and Fig. 2 a transverse section when the dovetail grooves in the 30 laths are all longitudinal. Figs. 3 and 4 show similar views when the one set of laths have longitudinal dovetails and the other set transverse. Fig. 5 is a plan of a panel cut on a skew.

35 In Figs. 1 and 2, *a a* are one set of laths, having longitudinal dovetail grooves *b*, and *c c* are the other set, also having longitudinal dovetail grooves *d*.

In Figs. 3 and 4, *e e* are one set of laths, 40 having longitudinal dovetail grooves *f*, and *g g* are the other set, having transverse dovetail grooves *h h*.

In both constructions the laths in each set are arranged side by side, and the dovetails 45 on one set of laths fit into the dovetail grooves on the other set. The side of adjacent laths of either set may abut against each other, as is shown at *k*, or adjacent laths may have tongues and grooves, as is shown at *l*.

In some cases it may be desirable to fit more than two sets of laths together.

The size of the laths may be varied. In constructing parquet-flooring one set of laths may consist of small lengths of different-colored woods, and, if desired, after they have 55 been fitted together a panel may be cut on the skew and the panels formed into a floor. This is shown in Fig. 5. *a a* are one set of laths, which are put together on the skew. The projecting ends *m* (shown in dotted lines) are cut 60 off, thus making a panel. The laths *a* may be made up of small lengths of different-colored woods, such as *n*.

In all cases after the laths have been fitted together the face may be polished, coated, papered, or ornamented in any way.

In this specification and in the claims the word "lath" is interchangeable with the words "block" or "board."

What I claim is—

1. Two sets of laths, the laths in one set having longitudinal dovetail grooves and the laths in the other set having transverse dovetail grooves, the dovetails on two adjacent laths of one set fitting into a dovetail groove 75 of a lath of the other set.

2. Two sets of laths, the laths in each set arranged side by side and abutting against one another, the laths in one set having longitudinal dovetail grooves and the laths in the 80 other set having transverse dovetail grooves, the dovetails on two adjacent laths of one set fitting into a dovetail groove of a lath of the other set.

3. Two sets of laths, the laths in each set 85 arranged side by side, a tongue on one lath fitting into a groove on the adjacent lath, the laths in one set having longitudinal dovetail grooves and the laths in the other set having transverse dovetail grooves, the dovetails on 90 two adjacent laths of one set fitting into a dovetail groove of a lath of the other set.

WALTER THOMAS CROSSE.
